UNITED STATES PATENT OFFICE.

WILLIAM G. WOODS AND NELSON T. SHAW, OF LOS ANGELES, CALIFORNIA.

DISPENSER.

Application filed June 3, 1924. Serial No. 717,654.

This invention relates to dispensers of the type employed in dispensing elongate articles. Important uses for the dispenser are the dispensing of cigarettes, cigars, matches, 5 toothpicks, and drinking straws, and the device may be used with great facility as an accessory to a motor car to enable the driver to readily obtain a cigarette or cigar while operating the vehicle.

10 An object of the invention is to insure against more than one article being dispensed at one time. This is a rather difficult matter with elongate objects, such as cigarettes, matches and the like.

15 Another object is to make provision for holding cigarette and cigar ashes and butts, thus insuring against occupants of automobiles equipped with the dispensers, throwing such ashes and butts along the roadside, a 20 procedure that often results in destructive forest fires.

Another object is to provide an automatic closure for the ash tray so that a 25 burning cigarette butt placed in the tray will be extinguished for lack of oxygen.

One of the important features of the invention is the provision of means for separating the article, that is to be ejected, from the other articles prior to such ejection, 30 thus avoiding jamming of the articles in the discharge opening.

A further object is to construct the device so that the separating member also acts as a closure or gate for the discharge opening.

35 Further advantages will appear herein-after.

The accompanying drawings illustrate the invention:

Fig. 1 is a front elevation of a dispenser 40 constructed in accordance with the provisions of this invention.

Fig. 2 is an end elevation from the right of Fig. 1.

Fig. 3 is a sectional elevation on the line 45 indicated by 3-3, Fig. 1.

Fig. 4 is a perspective view of the tray that constitutes a part of the closure means for the charging opening of the case.

Fig. 5 is a perspective view of the tray 50 cover that constitutes another part of the closure means mentioned above.

There is provided a case of any suitable shape, indicated in general by the character 55 11 and comprising vertical front and rear walls 12, 13, a bottom formed by a pair of

spaced strips 14, end walls 15, 16 and a downwardly and forwardly sloping top 17. In the top 17 is an opening 18 provided with a window 19, and the upper end of the top 17 is spaced from the rear wall 13 to form an 60 opening 20 which may be used for charging the device with the articles that are to be dispensed. The opening 20 will be closed by closure means indicated in general at 21 and described hereinafter in detail. The bottom 65 strips 14 are spaced from the front wall 12 to form a discharge opening 22. The strips 14 are bent downwardly and forwardly beneath the opening 22 to form receiving means 23 for the articles as they discharge 70 through the opening 22. Such articles are indicated at *a* in the form of cigarettes, though it is to be understood that other elongate articles such, for example, as cigars, matches and toothpicks may be dispensed 75 by constructing the parts of the invention in the right proportions.

Movably mounted inside of the case 11 is a U-shape member 24 provided in its bottom with a longitudinally extending slot 25. 80 The ends of the U-shape member 24 are pivoted at 26, 27 to the end walls 15, 16, respectively, so that the member 24 can swing forward and back within the case. The member 24 is normally held in its forward position, as in Fig. 3, by a spring 28 which has one end hooked into a hole 29 in the end wall 16 and its other end hooked at 291 over the rear edge of the U-shape member 24. The intermediate portion of the spring 28 is bent over the pivot 27.

To operate the member 24, the pivot 27 is provided with an operating arm 30 outside of the case which, when depressed, swings the member 24 rearwardly so as to bring the slot 25 over the bottom strips 14 rearwardly of the discharge opening 22. When the member 24 is in its forward position, the slot 25 registers with the discharge opening 22 and the bottom portion of the U-shape member 85 is aslant forwardly and upwardly.

To prevent the articles *a* from jamming to the rear of the member 24, when said member is swung rearwardly, there is provided a movably mounted floor member 31 which is 105 pivotally mounted by having end tongues 32 thereof entered in holes 33 in the end walls 15, 16. The floor member 31 extends aslant forwardly and downwardly and the forward end of said floor rests on the bottom portion 110

of the U-shape member 24. Naturally, as the U-shape member is swung rearwardly, it swings the floor member 31 upwardly.

When the member 24 is in its forward position, the slot 25 is substantially closed by a closure or gate member 34 which, in this instance, is movably mounted, being pivoted to the end walls by having its end tongues 35 entered in holes 36 in the end walls. The gate rests on the member 24 and when the member 24 is in its rear position the rear edge of the gate is below the level of the gate pivots so that said rear edge will move rearwardly when the gate swings upwardly. Preferably the gate 34 is concave from front to rear and, when the member 24 is swung rearwardly, the gate 34 swings downwardly by gravity. When the member 24 swings forwardly it swings the gate 34 upwardly to cause the rear end of the gate to enter between two adjacent articles *a*. When the member 24 swings rearwardly, the article *a* nearest the slot 25 drops into said slot, the article immediately forward of the one that drops into said slot being held out of contact with the one that drops by reason of the latter article resting on the gate 34.

Forward movement of the member 24 is limited by reason of said member engaging the ears 35 which thus function as stops. Rearward movement of the member 24 is limited by a stop 37 formed by an upwardly bent ear of one of the strips 14.

The operation of the construction thus far described is as follows:

Assuming that the device is loaded with cigarettes, when a cigarette is desired the operator will depress the arm 30, thus causing the member 24 to swing rearwardly. During this swinging movement, the rear end of the gate 34 swings downwardly, thus preventing the article that is in second place, in reference to the slot 25, from crowding between said slot and the article that is nearest to said slot which, thereupon, falls into the slot 25 and rests upon the strips 14. After depressing the arm 30, the operator removes his finger and the spring 28 immediately returns the member 24 to its forward position. Adjacent to the rear edge of the slot 25 on the member 24 is a downwardly projecting lip 38 that functions to shove the cigarette, that is in the slot, forwardly so that it passes through the opening 22 and falls into the receiving means 23. When the member 24 thus swings forwardly the gate 34 is swung upwardly and, accordingly, its rear edge moves rearwardly and pushes and rolls the cigarette in second place away from the slot 25, thus avoiding jamming of the second cigarette in the slot 25 and consequent injury to said cigarette.

The closure means 21, mentioned above, may be of any suitable construction and, in this instance, it constitutes an ash tray 39 and

cover 40. The ash tray is provided on its longitudinal edge with flanges 41 adapted to engage in grooves 42 in the inside face of the cover 40. The tray and cover are assembled by relatively sliding them endwise. The longitudinal margins of the cover 40 seat upon the walls 13, 17, respectively, to support the tray in the opening 20. The cover 40 is convex and the end margins of the cover seat upon the end walls 15, 16, respectively, which thus close the spaces existing between the tray and cover at the ends thereof. The cover 40 is provided with an opening 43 and with an apron 44 which extends aslant downwardly and rearwardly beneath the opening 43. Pivoted at its ends at 45 to the cover 40 is a gravity-closed shutter 46 that is normally in vertical position and closes against the inner end of the apron 44.

When the smoker desires to knock the ashes from his cigarette, he inserts the lighted end of the cigarette in the opening 43 and presses said end against the apron 44 or shutter 46. If he presses against the shutter, it will open and allow the ashes to fall into the tray. If he desires to throw his lighted cigarette away, he will push the cigarette against the shutter 46, forcing it open, and drop it into the ash tray, and the shutter will then close so as to prevent smoke from issuing from the tray and annoying the occupants of the vehicle.

We claim:

1. A dispenser comprising a case, a member movably mounted in the case and provided with a slot, a gate movably mounted in the case in position to close over the slot when the slotted member is in one position and to open the slot when said slotted member is in another position, said gate being moved by movement of the slotted member, and operating means for the slotted member.

2. A dispenser comprising a case, a member movably mounted in the case and provided with a slot, a gate pivotally mounted in the case in position to close over the slot when the slotted member is in one position and to open the slot when said slotted member is in another position, the gate resting on the slotted member, and operating means for the slotted member.

3. A dispenser comprising a case, a member movably mounted in the case and provided with a slot, a gate mounted in the case in position to close over the slot when the slotted member is in one position and to open the slot when said slotted member is in another position, a floor member pivotally mounted in the case and resting upon the slotted member, and operating means for the slotted member.

4. A dispenser comprising a case, a slotted member mounted to swing forward and back in the case, a gate pivotally mounted in the

case in position to close over the slot when the slotted member is in one position and to open the slot when said slotted member is in another position, the gate resting on the 5 slotted member, and means to swing the slotted member.

5. A dispenser comprising a case, a slotted member mounted to swing forward and back in the case, a gate pivotally mounted in the 10 case in position to close over the slot when the slotted member is in one position and to open the slot when said slotted member is in another position, a floor member pivotally mounted in the case, the gate and floor member resting on the slotted member, and means 15 to swing the slotted member.

6. A dispenser comprising a case, a member swingingly mounted in the case and provided with a slot, an upwardly concave gate pivoted to the case and resting upon said member in position to close over the slot when said member is in one position and to open the slot when said member is in another position, and operating means for the slotted member. 20
